(57) **CLAIM**

The ornamental design for a heel counter and midsole, as shown and described.

DESCRIPTION

FIG. 1 is a rear perspective view of a heel counter and midsole in use on an article of footwear;

FIG. 2 is a front perspective view of a heel counter and midsole in use on an article of footwear;

FIG. 3 is a lateral side elevational of the heel counter and midsole shown without the footwear environment;

FIG. 4 is a rear elevational view thereof;

FIG. 5 is a medial side elevational view thereof;

FIG. 6 is a top plan view thereof; and,

FIG. 7 is a bottom plan view thereof.

The broken lines in the drawings show features that form no part of the claimed design.

1 Claim, 6 Drawing Sheets
